UNITED STATES PATENT OFFICE.

WILLIAM N. MOORE, OF JOLIET, ILLINOIS.

DEVICE FOR FORMING STOVE-LUG MOLDS.

SPECIFICATION forming part of Letters Patent No. 289,685, dated December 4, 1882.

Application filed September 15, 1883. (No model.)

To all whom it may concern:

Be it known that I, WILLIAM N. MOORE, a citizen of the United States of America, residing at Joliet, in the county of Will and State 5 of Illinois, have invented certain new and useful Improvements in a Device and Process for Forming Stove-Lug Molds, of which the following is a specification, reference being had therein to the accompanying drawings.

10 Figure 1 is a perspective view of a pattern and molding-flask, showing the apparatus applied and in use; Fig. 2, a side elevation of this invention; Fig. 3, a vertical section of the case and side view of its interior mechanism; Fig. 4, a plan view on the top of a portion of a pattern, showing the slot a' and guide-lugs a^2 , it being the place at which the apparatus is applied as shown in Figs. 2 and 3; and Fig. 5, 15 a perspective view of a finished stove-lug cast 20 in the mold formed by the apparatus.

This invention consists in a device for forming the mold in the molding-sand of an ordinary flask, in which mold the lugs or ears which catch and support the doors of a stove 25 are cast.

Heretofore, in casting stove-plates, it has been usual to cast the lug A (shown in Fig. 5) solid, and then cut out the notch z afterward, during which operation a large percentage of 30 these lugs are injured or broken off, thus rendering the stove-plate worthless.

The apparatus herein described is for the purpose of forming the impress or mold in the sand in such manner that the lug is cast with 35 the notch z in it, as shown in Fig. 5, so that the notch is perfect and ready for use, and the danger of afterward cutting or filing it out obviated.

Referring to the drawings, B represents a 40 case containing the pattern a of a lug pivoted at x as its center of motion, and upon which pivot it swings or partially rotates, as shown in Figs. 2 and 3. To the upper side of the pattern a is pivoted or hinged a rod, d , extending upward and out through a vertical slot in the side of the case, and terminates in 45 the thumb-plate d , by means of which the pattern a is operated. The lug P on the side of the pattern a , in conjunction with the spring P' , causes the pattern a to return from the sand 50

after pressure on the rod d is released, so that it will stand in the position shown in Fig. 3.

The mode of operation is substantially as follows: The stove-plate pattern c has a slot, a' , at the place where it is designed to form a lug, A, on the casting, as shown in Fig. 4, and is also provided with little projections or guide-lugs a^2 , for the purpose of guiding the case B so that it will stand directly over slot a' , so that the pattern a can pass down through 60 said slot. The case B is placed in the position shown in Figs. 1, 2, 3, so as to stand directly over the slot a' of the stove-plate pattern. The rod d is then forced downward by pressure on the thumb-plate d until the lug-pattern a is 65 forced down into the sand S through the slot a' of the plate c until said lug-pattern stands in the sand in the position shown in Fig. 2. A release of the pressure on rod d permits the lug-pattern a to return by means of the spring 70

P' , as shown in Fig. 3, thus leaving its form molded in the sand, as shown at m in said Fig. 3, to form the mold for the lug A, (shown in Fig. 5,) which, when the plate c is cast, is integral with said plate, and has the notch z left 75 or cast in it, as shown in said figure. The lug-pattern a is so hinged or pivoted to the case B that after it has been forced into the sand, as stated, and commences to return, it will not drag against the walls of the mold m , 80 and especially that part forming the notch z , but will swing away from it, as shown by the dotted lines in Fig. 3, and thus leave its corners sharp and intact. The back of the pattern is cut to be eccentric with the pivot x , so 85 that when it draws from the sand it will not drag on the sand to disturb it. After the mold m has thus been formed, the case B is lifted off and the pattern c removed, when the mold is complete to receive the metal to form 90 the lug A. By this device the mold for the lug A is formed by pressing the pattern for it in the sand in such manner as to leave it complete for the metal, without any further manipulation or patching up by hand, as in ordinary cases. 95

I am aware stove-door lugs or catches have heretofore been cast with the notch in them, but not by having the mold formed by such a mechanism as I have described.

The swinging pattern *a* may be varied in form to make a pattern for lugs or projections on the side of a plate, where it is difficult to withdraw a pattern otherwise constructed from the sand.

Having thus described my invention, what I claim as new, and desire to secure by Letters Patent, is as follows, to wit:

1. The combination of the case *B*, pivoted lug-pattern *a*, having the lug *P*, pivoted rod *d'*, having the thumb-plate *d*, spring *P'*, and pattern *e*, having the slot *a'*, as and for the purpose set forth.

2. In the device described for forming lug-molds, a swinging pattern *a*, adapted to form the mold *m*, corresponding with it in form, as and for the purpose substantially as set forth.

3. In the device described for forming lug-molds, the swinging or pivoted pattern *a*, adapted to form the mold *m*, substantially as and for the purpose set forth.

WILLIAM N. MOORE.
